UNITED STATES PATENT OFFICE.

NORMAN J. SMITH AND WILLIAM F. LIZER, OF WATERLOO, IOWA, ASSIGNEES, BY
DIRECT AND MESNE ASSIGNMENTS, OF ONE-HALF TO SAID SMITH AND ONE-
HALF TO FRED W. PETT, OF WATERLOO, IOWA.

HOSE-NOZZLE BRUSH.

1,171,755.

Specification of Letters Patent.

Patented Feb. 15, 1916.

Application filed February 1, 1915. Serial No. 5,524.

To all whom it may concern:

Be it known that we, NORMAN J. SMITH and WILLIAM F. LIZER, citizens of the United States of America, and residents of 5 Waterloo, Blackhawk county, Iowa, have invented certain new and useful Improvements in Hose-Nozzle Brushes, of which the following is a specification.

Our invention relates to improvements in 10 hose-nozzle brushes, and the object of our improvement is to provide a rotary head upon a perforated hose-nozzle, said head having a brush-like outer part, and said head rotated by means of water actuated 15 mechanism contained within the nozzle. This object we have accomplished by the means which are hereinafter described and claimed, and which are illustrated in the accompanying drawings, in which: 20 Figure 1 is a vertical axial longitudinal section of our said improved device, with parts broken away. Fig. 2 is a vertical transverse section of the device shown in Fig. 1, taken on the line *a*—*b* thereof, and 25 looking in the direction of the arrow.

Similar numerals of reference denote corresponding parts throughout the several views.

The numeral 19 denotes a tube, one open 30 end of which is provided with a coupling part 20 for a hose or a pipe. The other end of the tube is conically expanded at 18, and closed by a partition or transverse wall 14.

The numeral 10 denotes a hollow cylindrical chamber having one end annularly thickened at 11. This thickened part is detachably secured to an outwardly flanged part of the chamber 18 by means of screws 12.

The partition wall 14 has on its left-hand 40 face a bearing 15 in which is seated the right-hand end of a rotary shaft 1 having three turbine-wheels 21 mounted thereon in spaced relation, and having outwardly directed V-shaped vanes 22. The numeral 13 45 denotes bosses on opposite sides of the left-hand face of the partition 14 and which are orificed to receive the right-hand ends of tubes 16, whose left-hand ends are closed. Each tube 16 has three spaced inwardly directed laterally inclined nozzles 17 adapted 50 to discharge water against the vanes of said turbine or overshot wheels 21. Said chamber 10 has its left-hand end conically diminished at 9, and has a cylindrical ex-

tension 8, the end of the latter part being 55 stopped by a closure 7 centrally orificed to receive the left-hand extremity of said shaft 1 therein.

The numeral 2 denotes a cup-shaped head 60 provided with a plurality of orifices 3 and concentrically mounted about the chamber part 8 on the outwardly extending end of the shaft 1 by means of a screw 5 or other convenient fastening means. Brush bristles 4 are mounted all over the outside 65 surface of the head 2. The left-hand end of the tubular part 8 has a plurality of orifices 6.

Operation: When any fluid, under pressure, such as water or compressed air, is 70 transmitted through the hollow parts 19 and 18 to and through the tubes 16 and out of 17 upon the vanes 22 of the overshot wheels 21, the latter, together with the shaft 1 and the brush-carrying head 2 are placed 75 in rapid rotation. Exhaust water from said tubes passes into the cylindrical tube 8, and is sprayed outwardly through the orifices 6, a large proportion of the fluid then passing through the head 2 by way of its orifices 3. Since the wheels 21 are of a turbine or overshot type, and the fluid under pressure is delivered to them tangentially from without the rims of the wheels, a powerful 80 leverage is exercised upon the shaft 1. This 85 leverage is such that water or other fluid under a comparative little amount of head, is able to continuously rotate the brush 2—4 effectively while the latter is being employed in cleaning various surfaces and 90 while thereby undergoing considerable friction.

The brush shown is of a type which is suitable for general cleaning purposes, but other forms may be used.

Having described our invention, what we claim as new, and desire to secure by Letters Patent, is:

1. In combination, a chamber adapted to be placed in communication with a source 100 of fluid supply under head, a rotor mounted in said chamber and adapted to be rotated by said fluid when passing through the chamber, said chamber having a delivery-nozzle provided with a plurality of small 105 peripheral orifices, a shaft extending axially from said rotor through said nozzle, and a hollow intersticed brush mounted on the

outer end of said shaft and surrounding the peripherally orificed part of said nozzle.

2. In combination, a nozzle adapted to be placed in communication with a supply of fluid under head, a rotary shaft in said nozzle, the end of the nozzle being inclosed and having a bearing-orifice through which said shaft extends, said nozzle having a plurality of small peripheral orifices near said end, and a cup-shaped peripherally orificed body detachably mounted on the outer end of said shaft, about the peripherally orificed part of said nozzle and per-

meable brushing-means mounted on the outside of said body adapted to receive water 15 passed under pressure from said nozzle through its peripheral orifices and through the peripheral orifices of said body while the latter is rotating about the nozzle.

Signed at Waterloo, Iowa, this 12th day 20 of Jan. 1915.

NORMAN J. SMITH.
WILLIAM F. LIZER.
